UNITED STATES PATENT OFFICE

WILLIAM E. LUNDGREN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

KNOCK-OFF MECHANISM FOR LOOMS

Application filed November 2, 1931. Serial No. 572,607.

This invention relates to mechanism provided for stopping a loom on the failure of a shuttle to properly enter the shuttle box. Such mechanism operates to stop the lay in its forward movement and also to release the shipper and disconnect the driving mechanism.

It is the object of my invention to provide improved means for yieldingly resisting and checking the forward movement of the lay. A further object of the invention is to provide means by which the yielding resistance to the lay may be conveniently increased or decreased.

15 My invention further relates to arrangements and combinations of parts which will be hereinafter described and more particularly pointed out in the appended claims.

A preferred form of the invention is shown 20 in the drawings, in which

Fig. 1 is a plan view of portions of a loom embodying my improvements;

Fig. 2 is a front elevation thereof, looking 25 in the direction of the arrow 2 in Fig. 1;

Fig. 3 is a sectional end elevation, taken along the line 3—3 in Fig. 1, and

Fig. 4 is a perspective detached view of my invention.

Referring to the drawings, I have shown 30 parts of a loom including a lay 10 having the usual cross shaft 11 and dagger 12, the point of the dagger being depressed by the action of the shuttle as it enters the shuttle box. I have also shown a portion of a breast-beam 35 14 secured to a loom side 15, and a portion of a shipper lever 16 engaged by a contact screw 17 adjustably threaded in the end of a knock-off member 20.

The member 20 is loosely mounted in a recess or guideway in a stand 22, secured to the under side of the breast-beam 14 by bolts 23. A flat spring 30 is formed from a plurality of separate spring leaves secured together at one end by a clamping bolt 31.

The member 20 is engaged near the middle of its length by an abutment or upward projection 33 on the stand 22, and one end of the spring-clamping bolt 31 is received in a recess 34 in the side of the abutment or projec-

tion, thereby preventing endwise displacement of the spring.

The knock-off member 20 is provided with an offset lug or shoulder 35 at its inner end, and the free end of the spring 30 is positioned to engage the projection 35 and thus prevent outward endwise movement of the member 20.

A cylindrical roll or fulcrum member 40 is positioned between the forward face of the spring 30 and a cam surface 41 formed on the inner side of a projecting portion 42 of the stand 22. An adjusting screw 44 is threaded into the projection 42 and engages the fulcrum member 40.

As the fulcrum member is forced inward, 65 its point of engagement with the spring 30 is advanced toward the free end of the spring, thus shortening and stiffening the spring. At the same time the roll 40 is forced rearward by the cam surface 41, thus bending the 70 middle portion of the spring rearward and placing it under greater tension. The action of the spring may thus be effectively increased or decreased by means of the adjusting screw 44.

The stand 22 is provided with an opening 50 at its rear side, thus permitting engagement of the dagger 12 with the knock-off member 20. The stand 22 is also provided with an elongated transverse recess or opening 51, permitting unobstructed movement of the dagger 12 when in the lowered inoperative position indicated in dotted lines in Fig. 3. If the shuttle fails to box, the dagger 12 will remain in the raised or operative 85 position indicated in Fig. 3 and as the dagger moves forward, the pointed end of the dagger will be received in a notch or recess 52 in the rear face of the knock-off member 20.

The knock-off member will then be pushed forward against the resistance of the spring 30 until the spring overcomes the inertia of the lay and prevents further forward movement of the member 20. At the same 95 time the swinging movement of the member 20 causes the screw 17 to engage and release the shipper lever 16 or to otherwise disconnect the driving mechanism.

The interval in which the lay is brought 100

to rest may be increased or decreased as desired by adjustment of the screw 44 to vary the tension of the spring 30.

The leaf spring construction is found particularly effective and satisfactory, as the resistance of the spring increases rapidly as it is displaced from normal position. Furthermore the tension of the spring may be very easily increased or decreased by the adjusting mechanism described. The construction of the device is such that no assembling labor is necessary, as the member 20, the spring 30 and the fulcrum member 40 are merely dropped into recesses in the stand 22 and require no attachment thereto.

Having thus described my invention and the advantages thereof, I do not wish to be limited to the details herein disclosed, otherwise than as set forth in the claims, but what

I claim is:—

1. In a loom, a knock-off member, a stand in which said member is movably mounted, means to move said knock-off member, a flat leaf spring having an end portion loosely seated in a recess in said stand, whereby said spring is held from endwise displacement, the opposite end portion of said spring engaging said knock-off member, and means engaging said spring between its end portions and effective to vary the tension of said spring.

2. In a loom, a knock-off member, a stand in which said member is movably mounted, means to move said knock-off member, a multi-leaf spring seated at one end in said stand and having its free end engaged by said knock-off member, and means to vary the tension of said multi-leaf spring.

3. In a loom, a knock-off member, a stand in which said member is movably mounted, means to move said knock-off member, a flat leaf spring seated at one end in said stand and having its free end engaging said knock-off member, a fulcrum member engaging said spring at a point intermediate its ends, and means to move said fulcrum member lengthwise of said spring.

4. The combination in a loom as set forth in claim 3, in which the knock-off member, the spring, and the fulcrum member are all loosely held in said stand but are unattached thereto.

5. In a loom, a knock-off member having a shoulder at one end, a stand in which said member is movably mounted, means to move said knock-off member, and a flat leaf spring engaging and yieldingly resisting swinging movement of said knock-off member and also engaging said shoulder on said member to prevent endwise displacement of said member.

6. In a loom, a knock-off member, a stand in which said member is movably mounted, means to move said knock-off member, a flat leaf spring seated at one end in said stand

and having its free end engaging said knock-off member, a fulcrum member engaging said spring at a point intermediate its ends, and means to move said fulcrum member to bend the intermediate portion of said spring toward said knock-off member.

7. In a loom, a knock-off member, a stand in which said member is movably mounted, means to move said knock-off member, a flat leaf spring seated at one end in said stand and having its free end engaging said knock-off member, a fulcrum member engaging said spring at a point intermediate its ends, said stand having a cam surface engaged by said fulcrum member, and means to move said fulcrum member along said cam surface, thereby shifting the fulcrum of said spring both longitudinally and transversely relatively to said spring.

In testimony whereof I have hereunto affixed my signature.

WILLIAM E. LUNDGREN.
